[57] CLAIM

The ornamental design for a cord lock for attachment to decorative woven wood shades, substantially as shown and described.

DESCRIPTION

FIG. 1 is a perspective view of a cord lock for selectively locking cords for attachment to hanging decorative woven wood shades showing my new design; FIG. 2 is a front elevational view thereof; FIG. 3 is a rear elevational view thereof; FIG. 4 is a side elevational view thereof; and FIG. 5 is a bottom plan view thereof.

The cords, shown in dashed lines in FIG. 1, are for illustrative purposes only and do not form a part of my new design.
